[57] ABSTRACT

A gas dispenser used for filling gas lighters carries a tightening body enclosing a filling tube extending from the neck of the dispenser. The front end of the tightening body fits around the front end of the filling tube and is resiliently adjustable so as to enclose the filling opening of a gas lighter and be adaptable to various shapes of gas lighters. The rear end of the tightening body is adapted to fit upon the neck of the dispenser and has a lesser axial resiliency than the front end.

TIGHTENING BODY FOR GAS DISPENSERS

This application is a continuation of my U.S. application Ser. No. 529,430, filed Feb. 23, 1966, now abandoned.

The present invention relates to a tightening body for use on the filling stud of gas dispensers for filling gas lighters and of the kind comprising a tightening member having a front surface for tightening against a ring formed area around the filling opening of the gas lighter and having a hole for being received axially slidably on said filling stud adjacent the outer end thereof, and resilient means connected with and projecting from said tightening member oppositely said front surface thereof, said resilient means having a holding portion spaced from said tightening member and adapted to be held against substantially nonslidable supporting means located adjacent the filling stud in distance from the outer end thereof.

For filling or refilling a gas lighter it is common practice to use a gas dispenser having a valve stud that is pressed into a filling opening in the lighter. By this pressure an inlet valve in the lighter is opened, and simultaneously the valve stud will be pressed back relatively to the gas dispenser container, whereby an outlet valve in the dispenser is opened so as to allow liquid gas to flow from the dispenser to the gas reservoir in the lighter. These valves close automatically when the dispenser is removed from the lighter.

Hitherto, there has been considerable difficulties in designing a gas dispenser for use in connection with all or most of the many different lighter types available on the market, because the necessary injection depth for the filling stud varies considerably from type to type. Therefore, the tightening means used must be able to assume many different positions along the filling stud, and with the use of a solid tightening body of resilient material such as known in the prior art it has not been possible to obtain a sufficient resiliency in order to make a gas dispenser fitted with such a tightening body applicable for filling gas lighters of all the different types.

The purpose of the present invention is to provide a tightening body of the kind referred to which will enable one gas dispenser to be used for filling practically every existing type of gas lighter due to a considerable improvement in the resilient movability of the tightening member relatively to said holding portion of the tightening body. According to the invention the said resilient means comprise resiliently bendable portions having a such inclined or curved configuration when seen in axial direction at least after initial movement of said tightening member towards the holding portion that further movement of the tightening member towards the holding portion causes an increase in the bending stress in said bendable portions without causing substantial axial compression of the resilient material. Hereby the tightening member may be moved over a relatively long distance being influenced by pressing force.

In the following the invention will be described with reference to the accompanying drawing, in which:

FIG. 1 is a side view partly in section of the top portion of a gas dispenser fitted with a tightening body according to a first embodiment of the invention,

FIGS. 2-4 are corresponding views illustrating the deformation of the tightening body shown in FIG. 1 in three stages during its movement when used for filling a certain type of gas lighter,

FIGS. 5 and 6 are corresponding views of the tightening body used by the filling of another type of gas lighter, and

FIGS. 7-9 are side views corresponding to FIG. 1 of three other embodiments of the tightening body according to the invention.

FIG. 1 shows the upper part of a gas dispenser 2 containing liquid gas under usual pressure conditions. In a neck portion 4 of the dispenser 2 there is mounted an outlet valve (not shown) operable by depression of a filling valve stud 6 projecting upwardly from the neck portion. The gas in the dispenser can flow out through this stud 6 when the same is depressed a short distance against the action of a valve spring such as well known in the art.

Over the stud 6 there is placed a prolongation pipe having a lower sleeve portion 8, a cone formed intermediate portion 10 and an outer filling pipe portion 12. This tube member consists of a relatively hard material for example as known under the trade mark "Delrin." Adjacent the outer end of the filling tube 12 there is provided one or more radial holes 14; these may also be provided as notches in the end surface of the filling pipe 12 as shown in FIG. 9.

The stud 6 and the tube member 8, 10, 12 are encircled by a tightening body 16 of resilient material such as rubber, this body having a lower holding portion fitting tightly around the lower end 8 of the prolongation tube member and resting on the top surface of the neck portion 4. The tightening body 16 is provided with a preferably egg-shaped cavity 18 behind or beneath its front end. This front end is designated with 20 and fits loosely around the filling pipe 12 so as to be axially slidable thereon.

In order to fill a gas lighter the dispenser 2 is turned upside down as shown in FIG. 2 and placed in alignment with the filling opening 26 of a gas lighter 24. The gas lighter 24 has a valve pin 28 adapted to the pressed downwardly for opening an inlet valve to the gas reservoir of the lighter. Such filling valves of the lighters are well known to those skilled in the art, and should, therefore, require no detailed description. The valve pin 28 may be provided with a pointed projection 30 located centrally for use as a center means for the outlet tube of the gas dispenser. When the dispenser is placed in the position shown the front end 20 thereof will be rested against the annular edge portion around the filling opening 26.

Hereafter the dispenser is pressed downwardly to the position shown in FIG. 3, in which the outer end of the filling pipe 12 contacts the valve pin 28. During this movement the end portion 20 of the tightening member 16 will be deformed and pressed against the wall of the filling pipe 12 whilst at the same time the wall of the cavity 18 is bent resiliently outwardly. Thereafter the dispenser 2 is pressed further downwardly to the position shown in FIG. 4. This movement should be made with sufficient force to overcome the opening resistance of the outlet valve in the dispenser as well as the inlet valve in the lighter. It appears from FIG. 4 that in this position the filling stud 6 has been pressed somewhat into the dispenser neck 4 while the valve pin 28 has been pressed downwardly in the lighter. By the movement to this position the tightening member constituted by the front portion 20 of the body 16 is pressed further backwardly on the filling pipe 12 without requiring any extra heavy pressure due to the presence of the cavity 18. Thus, the tightening member 20 will provide an effective seal at the top of the filling opening 26 so that gas cannot escape therefrom during the filling operation.

The pointed projection 30 may close the outlet opening of the filling tube 12, but in this case the gas can leave the filling pipe through the radial channels 14.

When the lighter has been filled, the dispenser 2 is removed therefrom whereby the movements of the various parts will be repeated in opposite order relatively to those described above.

In the embodiment of the lighter shown in FIGS. 2-4 the injection depth of the filling pipe 12 is relatively big. In the embodiment of the lighter shown in FIGS. 5 and 6 this depth is very small since the valve pin, here designated with 34, has its outer end situated almost in level with the outer surface of the lighter, where it is encircled by a ringformed rib 32. Since the outer end of the filling pipe 12 by the embodiment shown in projecting slightly beyond the front end 20 of the tightening body 16 it is easy to make sure that the filling pipe mouth is positioned correctly on the valve pin 34 so that this pin may thereafter be readily pressed down to the position shown in FIG. 6. The valves are not opened until after a certain displacement of the members 12 and 34 so that the front end of the tightening member will be pressed firmly against the ring rib 32 before the valves are opened. During the filling operation the entire front portion of the tightening member is pressed against the lighter so that also in this case a good tightening effect is obtained (FIG. 6).

Certain types of lighters require a relatively high valve-opening pressure that must be transmitted through the prolongation member 8, 10, 14. In the prior art it was found necessary to use a metallic outlet tubing on the gas dispenser in order to have this relatively high pressure transmitted without the risque of breaking the outlet tube. The filling pipe 12 of Delrin or corresponding artificial material as used with the invention is in fact breakable or bendable, but its strength and dimensions are so chosen that it is able to transfer the highest necessary pressing force but not substantially greater forces without breaking. Hereby it is ensured that the inlet valve of the lighter cannot be damaged by any excessive pressing force.

The material distribution in the tightening body 16 is chosen in such a manner that a sufficient tightening pressure against the edge of the filling opening is obtained already by the initial pressing thereagainst prior to any regular deformation of the tightening body, corresponding to the situation shown in FIG. 2. This pressure is built up substantially by a pure axial compression of the material in the tightening body. As the pressure is thereafter increased, the ringformed wall portion around the cavity 18 will be bent outwardly, but the extra pressing force necessary for this purpose is not very big so that the tightening or sealing pressure will not be considerably increased until the cavity 18 is completely pressed together. It will be appreciated, however, that the filling pipe 12 may project a long distance beyond the tightening member 20 before the cavity 18 is pressed together (FIG. 4).

In the embodiment shown in FIG. 7 the tightening body is shaped as a cap 36, and the resilient means between the neck of the dispenser and the front end of the tightening body are constituted by a cone formed helical spring 38. Due to the cone form the spring may be pressed down to plane configuration so that the tightening member can carry out substantial axial movement on the outlet tube from the dispenser.

The prolongation tubing 8 shown in FIG. 8 is provided with a bottom flange 40 serving as a supporting means for the holding portion of the tightening body, whereby the front end of the tightening body will be situated close to the mouth of the filling pipe 12 irrespectively of the length of the valve stud 6.

In FIG. 9 it is shown that the tightening body 16 may be placed directly on the outlet valve stud which is here shown somewhat enlarged and designated 42; as by the other embodiment it is not necessary that the tightening body 16 is mounted in touch with the neck portion 4 of the dispenser 2 because it will be pressed back such a supported position as soon as it is pressed against the filling opening of a lighter.

For the inventive idea it is without importance whether the front end of the tightening body is situated behind or beyond the outer end of the filling pipe 12 in the free or initial condition thereof.

What I claim is:

1. A tightening body for mounting on the filling and dispensing tube of a gas dispenser, the dispensing tube being an axially movable biased valve-actuated tube adapted to permit the passage of gas through the interior thereof, wherein the tightening body has a central passage receiving the dispensing tube, an outwardly tapered front end positioned around the outer end of the dispensing tube, slidably therealong and in continuous contact therewith, and intermediate resilient means extending rearwardly from the front end and having resiliently bendable material portions leaving an annular free space behind the front end and operable to be bent out from the axial direction in response to axial compression of the intermediate resilient means, and the intermediate resilient means having an abutment portion at the end thereof opposite the front end, the gas dispenser having rigid supporting means at a distance from the outer end of the dispensing tube, with the abutment portion being adapted to rest axially against the supporting means.

2. A tightening body as claimed in claim 1, wherein the intermediate resilient means are constituted by a resilient bushing being bellowlike deformable by axial compression.

3. A tightening body as claimed in claim 2, wherein the intermediate resilient means have a curved configuration in the initial condition thereof.

4. A tightening body as claimed in claim 3, in which the bushing and the tightening body is constituted by integral parts of a hollow resilient body provided with diametrically opposite holes for said valve stud.

5. A tightening body as claimed in claim 1, in which said resilient means are constituted by a helical spring.

10 6. A tightening body for mounting on the filling and dispensing tube of a gas dispenser for filling gas lighters, wherein the dispensing tube is an axially movable, biased valve-actuated tube adapted to permit the passage of gas through the interior thereof, comprising three integral portions, a first front portion consisting of a sealing member of

15 resilient material having a front end and a rear end and a central through-passage receiving the dispensing tube, with the front end being outwardly tapered and positioned around the outer end of the dispensing tube and slidably therealong, said front end remaining in continuous contact with said dispensing tube, a second portion having one end connected to the rear end of the first portion and consisting of resiliently bendable material arranged to only partially fill out the space behind the rear end of the first portion, the bendable material having a configuration providing for the bending thereof in response to axial compression of the front end of the first portion towards the second portion, the gas dispenser having rigid supporting means at distance from the outer end of the dispensing tube, and a third portion consisting of engagement means for being firmly rested against the supporting means.

30 7. A tightening body as claimed in claim 6, wherein said dispensing tube is a prolongation of and receivable on a filling stud of said gas dispenser and wherein said dispensing tube is a pipe bushing of Delrin.

8. A tightening body as claimed in claim 7, in which a radial passage is provided in the wall of said dispensing tube.

9. A tightening body according to claim 6, wherein the front portion is axially shorter than the third portion and is thicker than the second portion.

40 10. A tightening body in combination with a gas dispenser for gas lighters, the gas dispenser having a neck with a rigid surface, an axially movable, biased valve-actuated dispensing tube extending outwardly from the rigid surface terminating in a dispensing end and adapted to permit the passage of gas through the interior thereof, and a rigid supporting means at a distance from the dispensing end, wherein the tightening body has a central passage enclosing the dispensing tube and comprising a front outwardly tapering tightening portion surrounding and continuously contacting the dispensing end and having substantial axial and transverse resiliency, and a rear holding portion of lesser resiliency and adapted to be pressed axially tightly against the supporting means during dispensing.

50 55 11. A tightening body in combination with a gas dispenser according to claim 10, wherein the dispensing tube has an annular flange constituting the supporting means.

12. A tightening body for mounting on the filling and dispensing tube of a gas dispenser for filling gas lighters, 60 wherein the dispensing tube is an axially movable, biased valve-actuated tube adapted to permit the passage of gas through the interior thereof, comprising three integral portions, a first front portion consisting of a sealing member of resilient material having a front end and a rear end and a central through-passage receiving the dispensing tube, with the front end being outwardly tapered and positioned around the outer end of the dispensing tube and slidably therealong, said front end remaining in continuous contact with said dispensing tube, a second portion having one end connected to the rear end of the first portion and consisting of resiliently bendable material arranged to only partially fill out the space behind the rear end of the first portion, the bendable material having a configuration providing for the bending thereof in response to axial compression of the front end of the first portion towards the second portion, the gas dispenser having rigid

supporting means at a distance from the outer end of the dispensing tube, and a third portion consisting of engagement means for being firmly rested against the supporting means, said tube comprising prolongation of the outlet passage of a valve stud receivable within said third portion opening, and formed as a lower stud-engaging cylindrical portion, an inter-

mediate portion of decreasing diameter against which said tightening body front portion is engageable to actuate said valve, a coaxial outer filling pipe portion projecting through said front portion opening and about which is slidably received said front portion.
